UNITED STATES PATENT OFFICE

159,308

FLOCKED FABRIC

Joseph Alexander, New York, N. Y.

Application February 10, 1950, Serial No. 7,876

Term of patent 3½ years

(Cl. D92—1)

To all whom it may concern:

Be it known that I, Joseph Alexander, a citizen of the United States of America, residing in New York city, county of New York, and State of New York, have invented a new, original, and ornamental Design for a Flocked Fabric, of which the following is a specification, reference being had to the accompanying drawing, forming part thereof, wherein the figure on the drawing is a plan view of a flocked fabric showing my new design, a design unit of which is outlined by broken lines and is repeated lengthwise between the selvage edges of the fabric.

I claim:

The ornamental design for a flocked fabric, substantially as shown and described.

JOSEPH ALEXANDER.
